Primary Examiner—Robert M. Spear
Attorney, Agent, or Firm—Gerry S. Gressel; Larry L. Huston; Roddy M. Bullock[57] CLAIM

The ornamental design for a pattern for a nonwoven wipe, as shown and described.

DESCRIPTION
